CARL DIETERICH, OF ROSLINDALE, (WEST ROXBURY,) MASSACHUSETTS.

Letters Patent No. 88,776, dated April 13, 1869.

IMPROVED FOLDING-CHAIR.

The Schedule referred to in these Letters Patent and making part of the same.

To all persons to whom these presents may come:

Be it known that I, CARL DIETERICH, of Roslindale, of the town of West Roxbury, of the county of Norfolk, and State of Massachusetts, have invented a new and useful Improvement in Folding-Chairs; and do hereby declare the same to be fully described in the following specification, and represented in the accompanying drawings, of which—

Figure 1 is a side elevation,

Figure 2, a front view, and

Figure 3, a vertical section of one of my chairs as unfolded, or with its parts in positions for a person to sit upon the seat.

Figure 4 denotes a front elevation, and

Figure 5, an edge view of the chair in a folded state.

In this chair, the legs and the side-bars of the back are formed by four levers, or bars, A A', B B'.

Each of the shorter levers, B or B', covers one of the back levers, A or A', and the two are connected, near the crossing, by a joint-pin, or screw, a, going through an ear, or short arm, b, projecting forward from the longer or back-bar lever, or from a plate, c, fastened to the outer side of the same.

The pair of back-bars, or levers A A', is connected by a series of bars, d e f g, extending between and from one to the other of them, and being arranged in manner as represented.

The back, h, is secured to the upper two of such bars, and also to the levers A A'.

Furthermore, the pair of shorter levers, B B', is connected by two bars, i k, going from one to the other of them.

There is an arm-rest, or flexible band, E, fastened to the upper part of each shorter lever, and extended and secured to the longer lever, in manner as represented.

The seat, shown at F, is connected with each of the back-bars, or levers by means of one of two short bars, G G, and by screws going through the said bar at its end. One of such screws goes through the bar, and

is screwed into the seat. The other screw goes through the bar, and is screwed into the back-lever. In other words, each link-bar G is to be pivoted both to the seat and to the back-bar.

The seat is also provided with two hooks, or stops, l l, to hook, or bear against studs m m, (projecting inward from the shorter levers B B',) when the chair is in an unfolded state, or its parts in the positions as indicated in figs. 1, 2, and 3.

When the chair is folded, the seat will be turned down into, or about into, parallelism with the two sets of levers, A A', B B', and the connections G G will overlap the studs m m. The ears, or arms b b will cause the shorter levers, when folded, to be in advance of and parallel, or nearly so, with the longer ones, in manner as shown in figs. 4 and 5. They also bring the pivots of the legs nearer the middle of the seat than would be the case were they to go through the four levers, as in various other folding-chairs.

The peculiar advantage of the ears b b and the connection-bars G G, applied to and arranged with the seat and the two sets of levers, A A', B B', in manner as explained, is, that they enable such parts to be folded together in a better manner than they can be in various other chairs, and, besides, the connections G G allow the seat to rise upward, while being folded, from a horizontal to a vertical position.

What I claim, in the above-described folding-chair, is—

The arrangement and combination of the ears b b, and the connection-bars G G, with the seat and the two sets of levers, the said bars and ears being connected with the said seat and levers in manner substantially as described.

CARL DIETERICH.
